CEMETERY VASE

George W. Hagle, Hillsboro, Oreg.

Application January 23, 1940, Serial No. 315,235

8 Claims. (Cl. 47—41)

This invention relates to improvements in ground vases and pertains particularly to vases of the type employed in cemeteries.

The present invention has for its primary object to provide an improved ground or cemetery vase, having a fixed portion and a removable portion which telescopes thereinto, in which a novel means is employed for supporting the removable portion in upright position, which means also functions as a holder or securing means for the said removable portion when the latter is re-inserted in the fixed portion in inverted position whereby the inserted removable portion will be securely held in place.

Another object of the invention is to provide in a ground or cemetery vase including a fixed portion and a removable portion, a novel spring supporting means forming a part of the fixed portion for holding the removable portion in upright or operative position and for yieldingly checking the downward movement of the removable portion as it is inserted in the fixed portion to prevent damage to the said removable portion, such spring supporting means further acting as a yieldable securing element which engages within the mouth of the removable portion when the latter is placed in the fixed portion in inverted position.

Another object of the invention is to provide in a ground or cemetery vase structure of the character stated, a removable portion having an outwardly expanded encircling wall area which functions to prevent debris entering the fixed ground portion when the removable portion is in upright operative position and which cooperates with the spring supporting means for the removable portion to effect the latching of the latter portion in the ground portion thereby preventing the removable portion from being raised by a rapid accumulation of water in the fixed portion of the device.

A further object of the invention is to provide in a cemetery ground vase, a novel end wall structure and handle associated with the end wall, for the removable portion of the vase whereby such handle will be protected against damage when the said removable portion is dropped into the fixed ground portion onto the spring supporting means within the fixed portion.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifica-

tions mark no material departure from the salient features of the invention as expressed in the appended claims.

In the drawing:

Fig. 1 is a view in longitudinal section through the vase structure embodying the present invention showing the removable portion in upright position.

Fig. 2 is a vertical sectional view similar to Fig. 1, but showing the removable portion in inverted position and latched in the fixed portion.

Referring now more specifically to the drawing, the numeral 1 generally designates the fixed portion of the vase structure while the removable portion is indicated generally by the numeral 2. Both of these portions are of cylindrical form and are formed of a sheet metal of suitable weight and character to resist rusting or corrosion when left in the ground. The fixed outer portion 1 of the vase comprises the cylindrical wall 3 which is rolled outwardly at its upper end to form a reinforcing bead 4 while at its lower end it is provided with the narrow inturned flange 5. Disposed within the lower part of the fixed portion 1 is a supporting unit indicated generally by the numeral 6 and comprising a substantially triangular frame of resilient metal having a horizontal top portion 7 and the downwardly converging legs 8 and 9 extending from the ends of the horizontal portion 7 as shown, the leg 9 being free while the leg 8 continues downwardly at substantially the central part of the cylinder to join the lateral arm 10 which extends horizontally to the side of the cylinder where it is riveted or otherwise suitably secured to the cylinder wall, as indicated at 11. The end of the leg 9 which is joined with the horizontal bar 7 is shaped to form the rounded knee 12 which is disposed either against or in close proximity to the inner surface of the cylinder wall 3, but by reason of the resilient character of the frame, this knee may be forced away from the wall to permit another element to move into position between the wall and the knee in the manner hereinafter stated.

To the top of the resilient frame portion 7 there is secured a disk 13 of resilient metal which is dished whereby the remote edge portions thereof are raised from the portion 7 of the frame to serve as an auxiliary spring support for the removable portion 2. The removable portion 2 of the vase is also formed of a cylindrical body 14, which is open at one end and rolled to form the reinforced mouth flange or bead 15. At the opposite end or bottom of the portion 2 is a metal wall 16 which is set inwardly from the adjacent end of

the cylinder 14 and is provided with the integral flange 17 which extends to the end of the cylinder and engages the inner side of the cylinder wall, this flange merging with an outwardly extending 5 reverted flange 18 which grips the surrounding flange 19 which forms an integral part of the cylinder 14, thus securely locking the cylinder wall 14 and the end wall 16 together to form a water-tight joint and locating the end wall 10 inwardly of the plane of the adjacent end of the cylinder.

The central portion of the end wall 16 has the circular depression 20 therein which forms a finger recess and extending across this recess in 15 the plane of the wall 16 is a finger bar 21 which facilitates lifting the removable portion 2 when the same is in inverted position within the outer portion, as shown in Fig. 2.

Adjacent the outer end of the removable portion 2, the wall 14 is provided with the encircling outward bulge 22, the exterior diameter of which is only slightly less than the interior diameter of the fixed cylindrical portion 1, and the formation of this bulge provides within the removable 25 portion 2 the annular recess 23.

The bulge 22 is spaced from the inner or bottom end of the removable portion 2 such a distance that when the bottom of the removable portion is resting upon the disk 13 and the removable portion is supported by the removable frame 6, it will just enter the mouth of the fixed portion 1 and thus completely close the same, as illustrated in Fig. 1, and the knee portion of the resilient supporting frame 6 is so spaced with 35 respect to the bottom of the fixed portion that when the removable portion 2 is inverted and forced downwardly into the fixed portion so that the open edge of the removable portion will slip past the knee 12, the removable portion when 40 brought to rest upon the base or bottom flange 5 will have the knee 12 of the resilient support engaged in the annular recess 23. Thus the recess and knee cooperate to form a latching or securing means by which the removable portion 45 of the vase will be held in position and thus prevented from being raised or floated in the event of a heavy or sudden fall of rain filling the outer portion of the device with water.

It will also be noted that the overall diameter 50 of the interlocked flanges 18-19 in the bottom of the removable portion is substantially equal to the interior diameter of the fixed portion so that when the removable portion is in upright position as shown in Fig. 2, this flange will cooperate with the bulge 22 to hold the portion 2 against movement or wobbling and when the portion 2 is in inverted position as shown in Fig. 2, the flange will engage the wall 3 so as to close the upper end of the fixed portion and prevent 60 the entrance of dirt thereinto.

The overall length of the removable portion 2 is also slightly less than that of the fixed portion so that when the portion 2 is in inverted position, its bottom and the flanged edge thereof 65 will be slightly below the plane of the mouth of the portion 1 and, therefore, will not be damaged by the running of grass cutting machines or other apparatus over the vase.

While there has been shown and described a 70 dished resilient disk 13 secured to the horizontal top portion 7 of the resilient frame, it is to be understood that this disk may be discarded if desired, so that the removable inner portion will be supported directly upon the horizontal bar 7 75 of the resilient frame.

What is claimed is:

1. A cemetery vase of the character stated, comprising a ground engaging outer portion and a removable inner portion, said inner portion having an end wall closing the same and having its opposite end open, a supporting unit within one end of the outer portion upon which said end wall is adapted to rest to maintain the inner portion in upright position, said inner portion being adapted to be inverted and inserted with 10 its open end downwardly into the outer portion and over said supporting unit, the said supporting unit entering the open end of the inverted portion and engaging and resiliently securing the same in the outer portion. 15

2. A cemetery vase, comprising inner and outer separable cylindrical bodies, a resilient support disposed within the outer body adjacent one end and secured to the outer body, the inner body having one end closed by a wall and having its 20 other end open, the resilient support being designed to engage said end wall to maintain the inner body in upright position in and projecting at its upper end from the end of the outer body remote from said support, said inner body 25 when inverted and inserted into the outer body receiving the resilient support in its open end, the resilient support including a part resiliently held in close proximity to the inner surface of the wall of the outer body between which part 30 and the said wall of the outer body the wall of the inserted inner body of the inverted inner body slidably extends to be frictionally held by said part of the support.

3. A cemetery vase, comprising inner and outer separable cylindrical bodies, a resilient support disposed within the outer body adjacent one end and secured to the outer body, the inner body having one end closed by a wall and having its other end open, the resilient support being designed to engage said end wall to maintain the inner body in upright position in and projecting at its upper end from the end of the outer body remote from said support, said inner body when inverted and inserted into the outer body receiving the resilient support in its open end, the resilient support including a part resiliently held in close proximity to the inner surface of the wall of the outer body between which part and the said wall of the outer body the wall of the 50 inserted inner body of the inverted inner body slidably extends to be frictionally held by said part of the support, the wall of said inner body having a recess upon its inner side into which the said part of the resilient support engages. 55

4. A cemetery vase, comprising inner and outer separable cylindrical bodies, a resilient support disposed within the outer body adjacent one end and secured to the outer body, the inner body having one end closed by a wall and having 60 its other end open, the resilient support being designed to engage said end wall to maintain the inner body in upright position in and projecting at its upper end from the end of the outer body remote from said support, said inner body 65 when inverted and inserted into the outer body receiving the resilient support in its open end, the resilient support including a part resiliently held in close proximity to the inner surface of the wall of the outer body between which part 70 and the said wall of the outer body the wall of the inserted inner body of the inverted inner body slidably extends to be frictionally held by said part of the support, the wall of said inner body being provided with a surrounding outward 75

bulge having an exterior diameter substantially equaling the interior diameter of the outer body and arranged to close the said remote end of the outer body when the inner body is uprightly 5 carried by the support, the said bulge forming an annular recess upon the interior of the inner body in which the said outer part of the resilient support frictionally engages.

5. A cemetery vase, comprising an outer 10 cylinder open at both ends and having an inwardly projecting flange at its lower end, a resilient frame supported within the outer cylinder adjacent said lower end and including a knee portion disposed adjacent the inner wall of the 15 cylinder, an inner cylinder adapted for longitudinal extension into the outer cylinder through the outer end thereof, the inner cylinder being closed by a bottom wall, said inner cylinder having an outpressed annular bulge in the wall thereof 20 of remote from said end wall and having a diameter and being spaced from the end wall to position in and close the outer end of the outer cylinder when the end wall is resting upon said resilient support, the inner cylinder being insertible into 25 the outer cylinder in inverted position and receiving said support when so inverted, the wall of the inner cylinder when inverted being frictionally engaged between said knee and the wall 30 of the outer cylinder in the circular area defined by said bulge.

6. A cemetery vase comprising an outer cylinder open at both ends and having an inwardly projecting flange at its lower end, a resilient frame supported within the outer cylinder adjacent said lower end and including a knee portion disposed adjacent the inner wall of the cylinder, an inner cylinder adapted for longitudinal extension into the outer cylinder through the outer end thereof, the inner cylinder being closed by a bottom wall, said inner cylinder having an outpressed annular bulge in the wall thereof 35 remote from said end wall and having a diameter and being spaced from the end wall to position in and close the outer end of the outer cylinder when the end wall is resting upon said resilient support, the inner cylinder being insertible into the outer cylinder in inverted position and receiving said support when so inverted, the wall of the inner cylinder when inverted 40 being frictionally engaged between said knee and the wall of the outer cylinder in the circular area defined by said bulge, the said end wall of the inner cylinder being joined with the wall of the inner cylinder by an outwardly projecting 45 flange having a diameter substantially equaling the interior diameter of the outer cylinder whereby to close the outer end of the outer cylinder when the inner cylinder is in the said inverted position, the inner cylinder being of 50 slightly less overall length than the outer cylinder.

7. A cemetery vase, comprising an outer cylinder open at both ends and having an inwardly extending flange at its bottom end, an inner cylinder insertible into the outer cylinder and having a wall closing its inner end, a substantially triangular resilient frame disposed within the lower portion of the outer cylinder and having a horizontal bar and two downwardly converging legs extending from the bar, one of 5 said legs being joined with the bar to form a rounded knee disposed in close proximity to the wall of the outer cylinder, the other of said legs being integrally connected with the wall of the outer cylinder, the inner cylinder when in upright position having its bottom resting upon the 10 bar of said frame with its upper end projecting above the outer cylinder, the wall of the inner cylinder having an outpressed bulge adjacent its outer end, said bulge being arranged to close the outer end of the outer cylinder when the inner cylinder is in said upright position, the inner cylinder when inverted in the outer cylinder receiving said frame and having its wall slidably disposed between said knee and the wall of the outer cylinder to be frictionally held thereby 15 and said knee engaging the wall of the inner cylinder in the recess formed by said outpressed bulge.

8. A cemetery vase, comprising an outer cylinder open at both ends and having an inwardly 20 extending flange at its bottom end, an inner cylinder insertible into the outer cylinder and having a wall closing its inner end, a substantially triangular resilient frame disposed within the lower portion of the outer cylinder and having 25 a horizontal bar and two downwardly converging legs extending from the bar, one of said legs being joined with the bar to form a rounded knee disposed in close proximity to the wall of the outer cylinder, the other of said legs 30 being integrally connected with the wall of the outer cylinder, the inner cylinder when in upright position having its bottom resting upon the bar of said frame with its upper end projecting above the outer cylinder, the wall of the inner cylinder having an outpressed bulge adjacent its outer end, said bulge being arranged to 35 close the outer end of the outer cylinder when the inner cylinder is in said upright position, the inner cylinder when inverted in the outer cylinder receiving said frame and having its wall slidably disposed between said knee and the wall of the outer cylinder to be frictionally held thereby 40 and said knee engaging the wall of the inner cylinder in the recess formed by said outpressed bulge, and a resilient disk of dished form 45 secured to the top of the bar of said frame for contact with the end wall of the inner cylinder when the latter is in upright position in the outer cylinder.

GEORGE W. HAGLE.
